UNITED STATES PATENT OFFICE

OLIVER S. JENNINGS, OF MANSFIELD, OHIO, ASSIGNOR TO WESTINGHOUSE ELECTRIC & MANUFACTURING COMPANY, A CORPORATION OF PENNSYLVANIA

SWITCH MECHANISM

Application filed June 4, 1927. Serial No. 196,466.

My invention relates to switch mechanism and particularly to enclosed switch mechanism for controlling circuits of industrial small motors.

5 One object of my invention is to provide switch mechanism wherein the switch is moved to open and closed positions with a snap action and wherein the switch actuating mechanism is principally constructed of sheet metal stampings that may be inexpensively manufactured and readily assembled.

10 Another object of my invention is to provide an improved means for supporting the switch operating bail in order to reduce the 15 wear and at the same time prevent the entrance of dust and foreign matter through openings usually provided for supporting the bail.

Another object of my invention is to provide 20 an improved means for connecting the switch blade to the operating bail.

These and other objects that will be made apparent throughout the further description of my invention are attained by means of the 25 switch mechanism hereinafter described and illustrated in the accompanying drawings wherein,

Figure 1 is a front elevational view of an 30 enclosed switch, embodying features of my invention, the cover being shown as partly cut away,

Fig. 2 is a side elevation of the switch mechanism shown in Fig. 1,

Fig. 3 is a transverse section through the 35 switch mechanism taken on the line III—III of Fig. 1,

Fig. 4 is an exploded perspective view of the switch actuating mechanism and,

Figs. 5 and 6 are longitudinal sections 40 taken on the line V—V of Fig. 1 showing the switch operating mechanism in closed and open positions, respectively.

Referring to the drawings, the apparatus 45 comprises a sheet metal housing 7 having oppositely disposed side walls 8 and 9, end walls 11, and a bottom wall 12. The housing is provided with a cover 13 that is pivoted upon hinge rivets 14.

An insulating base 16 is secured to the bottom wall of the housing and carries the usual

55 fuse receptacles 17 and mountings for knife switches 18 which include the hinge jaws 19 and the contact jaws 21.

The switch blades 18 are connected to a switch operating bail 22 by means of a pair of metal arms 23 that are attached to clips 24 secured to an insulating bar 25. The insulating bar is fixed to the switch blades 18.

60 The arms 23 are each provided with a socket bearing 26 into which the bail is inserted through a notch 27 disposed between integral pin eyelets 28, as indicated in Figs. 1 and 2. The bail is held in assembled position within the socket 26 by means of cotter pins 29 that are inserted through the eyelets 65 28. This construction provides an inexpensive switch arm and facilitates its assembly.

65 Referring particularly to Figs. 2, 3 and 4, the switch operating mechanism comprises a pair of discs 31 and 32 which are disposed 70 on opposite sides of the side wall 9 and which are riveted together by means of shoulder rivets 33. The inner disc 32 is provided with a countersunk portion 34 which constitutes a journal that rotates within the bearing 75 opening 35 in the side wall 9. An operating handle 36 made of a round iron bar is attached to the outer disc 31. As indicated in Figs. 2, 3 and 4, the operating handle comprises an integral eyelet 37 that is attached 80 to the disc 31 by means of the integral flange 38 of the disc 31 which is spun over the eyelet to fix it in position and to prevent relative 85 rotary movement of the operating handle with respect to the disc.

The side wall 8 is provided with a closed socket 39 for receiving the journal end of the bearing 41 and the disc 32 is provided with a similarly closed socket 42 for receiving the journal end 43 of the bail 22. The 90 bail is assembled within the sockets by compressing the ends thereof toward one another and snapping it into assembled positions, as shown in the drawing. By reason of this construction the bearing opening 95 35 is closed and there is no opening at the socket 39. Therefore, dust and foreign substances are excluded at these points and because of the broad wearing surfaces presented the wear is reduced to a minimum.

The bail 22 is operated by means of an actuating plate 44 that is mounted for limited rotation upon the journal 43 of the bail, the bearing for the plate comprising a bushing 45 that is drawn from the plate 44 and which constitutes an integral part thereof.

For reasons which will hereinafter appear, it is desirable to provide a lost motion connection between the operating handle and 10 the actuating plate 44 in order to permit of limited movement of the actuating handle before the plate is rotated thereby. For this purpose the plate 44 is provided with a pair of arcuate slots 46 through which the shoulder rivets 33 extend and which permit of limited movement of the plate 44 with respect to the operating handle.

The plate 44 is retained in assembled relation to the operating handle by means of 20 the shoulder rivets 33 which extend through a retaining washer 47, as indicated in Fig. 3. The washer 47 fits over the shoulder bearing 45 of the disc 44.

The actuating disc 44 is provided with a 25 peripheral flange 48 having a slot 49 for receiving the bail 22 which is inserted through the opening 51 in the flange 48. By reason of the slot 49 a lost motion connection is provided between the actuating plate 44 and 30 the bail 22, the purpose of which will hereinafter appear.

In order to impart a snap action opening and closing movement to the switch blades, the actuating disc 44 is pivotally connected 35 to an over-center compression spring 52 that surrounds a guide bar 53 having an enlarged end member 54 that is pivotally attached to the disc by a pin 55. The free end of the bar operates in a slot 56 in a guide clip 57 that 40 is pivoted to the side wall 9 of the housing by a pin 58. The spring 52 is disposed between the enlarged portion 54 of the guide bar and the clip 57 and serves to move the disc 44 to either of its extreme positions with 45 a snap action.

The movement of the disc is limited by means of a stop lug 59 that is stamped from the side wall 9 and which is engaged by a lug 61 on the disc or plate 44 when the disc is 50 in its extreme closed position, as shown in Fig. 5, and by the lug 62 when the disc is in the open position, as shown in Fig. 6.

Assuming that the switch is in the closed position, shown in Figs. 1, 2, 3 and 5, the 55 switch is opened by moving the operating handle 36 clockwise as shown in Figs. 5 and 6. The initial movement of the operating handle moves the shoulder rivets 33 into engagement with the ends 63 of the slots 46.

Further movement of the operating handle 60 causes clockwise rotation of the actuating disc 44, thus compressing the spring 52 until the pin 55 passes the center line between the axes of the disc 44 and the pin 58. During this movement of the operating handle and

the disc 44 the end 64 of the slot 49 engages the bail 22 and causes initial movement of the switch blades 18 toward open movement. The spring 52 passes over the previously referred to center line just prior to the separation of the blades 18 from their contact jaws 21. The instant the spring has passed over center it causes rotation of the actuating disc to open position with a snap action, thus forcing the switch blades to open position 75 with a rapid movement. The movement of the actuating disc is limited by the lug 62 which engages the stop lug 59.

Since a lost motion connection is provided between the operating handle and the actuating disc, and a lost motion connection is also provided between the actuating disc and the bail, the switch moves to open position regardless of whether the operating handle is being held by the operator or not. Should the spring fail or should the contacts seize and prevent the spring from opening the switch, the switch may be positively actuated to open position by moving the operating handle to its full open position.

In order to close the switch, the operating handle 36 is moved in the opposite direction. Initial movement of the operating handle imparts no movement to the actuating disc 44 until the shoulder rivets 33 engage the ends 65 of the slots 46. Further movement of the operating handle causes counter-clockwise rotation of the actuating disc until the spring 52 is again moved over center, at which time the disc will be moved to closed position with a snap action, carrying with it the bail 22 which moves the switch to closed position with a snap action. The final closing movement of the switch under the influence of the spring 52 occurs regardless of whether the operating handle 36 is held by the operator. The switch may be locked in the "on" or "off" position by placing a padlock hasp through perforations 66 and 67 in the clip 68 and the flange 69 respectively. The clip 68 is secured to the exterior side of the wall 9 and the flange 69 is integral with the disc 31.

It is apparent from the foregoing that a simple, inexpensive, quick-make and quick-break operating switch mechanism is provided. Because the parts constituting the switch operating mechanism are stamped from sheet metal, the overall thickness of the switch operating mechanism is materially reduced and therefore the space required for the switch is reduced to a minimum.

While I have illustrated but one embodiment of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. Switch mechanism comprising a housing having side walls, one of which is provided with a bearing opening, a pair of discs of larger diameter than the opening disposed on opposite sides of the said side walls and secured together by a pair of shoulder rivets, one of the discs having a journal fitting within the opening and centering the said discs for rotation about the axis of the bearing opening and the inner disc having a centrally disposed bearing socket, an operating handle attached to the outer disc, a movable switch within the housing, an operating member therefor pivoted at one end in the said socket, an actuating member rotatably mounted on the operating member and having a lost motion connection thereto, the actuating member being provided with arcuate slots through which the shoulder rivets extend for providing a lost motion connection to the operating handle, the said rivets serving to retain the actuating member in assembled relation to the operating handle, and a spring for moving the actuating member to either of its extreme positions with a snap action.
2. Switch mechanism comprising a movable switch member, an operating bail therefor, a support, a bail operating plate rotatably mounted in the support and provided with an annular flange and an operating handle comprising a rod having an eyelet at one end attached to the plate by portions of the said flange.
3. An operating handle for a switch comprising a bar provided with an integral eyelet at one end, and a flanged plate provided with means for connecting to a switch member, the said plate being attached to the eyelet by means of portions of the flange bent around the eyelet portion of the handle.
4. A switch arm comprising a sheet metal plate having a bearing socket for a switch operating bail formed between two integral pin eyelets, and a cotter pin fastened in the said eyelets to prevent accidental removal of the said bail.
5. Switch mechanism comprising a housing having oppositely disposed side walls provided with opposite closed bearing sockets, a switch within the housing, a flexible operating bail of greater length than the space between the side walls of the housing and adapted to be sprung into the said sockets, and means accessible exteriorly of the housing for actuating the said bail.

In testimony whereof, I have hereunto subscribed my name this 17th day of May, 1927.

OLIVER S. JENNINGS.
